UNITED STATES PATENT OFFICE.

EDWARD L. GUSTAFSON, OF HOLDREGE, NEBRASKA.

WASHING MACHINE.

Application filed February 11, 1925. Serial No. 8,463.

To all whom it may concern:

Be it known that I, EDWARD L. GUSTAFSON, a citizen of the United States, residing at Holdrege, in the county of Phelps and State of Nebraska, have invented certain new and useful Improvements in Washing Machines, of which the following is a specification.

This invention relates to washing machines adapted for occasional use and for small articles; and it consists in the novel construction of the same as hereinafter fully described and claimed.

In the drawings, Figure 1 is a vertical section through a machine constructed according to this invention with the sink lid removed, and is taken on the line 1—1 in Fig. 2. Fig. 2 is a plan view of the same. Fig. 3 is a detail front view of the toothed segment and removable handle. Fig. 4 is a side view of the same. Fig. 5 is a detail front view of the handle. Fig. 6 is a front view of the sink when closed by its lid, and is drawn to a smaller scale.

A rectangular vessel 8 is provided, and is divided into two compartments 9 and 10 by a partition 12. The smaller compartment or chamber 9 is closed by a removable lid 14 when the washing machine is not in use. The larger compartment 10 has a drain pipe 15 for water at its bottom. The vessel 8 is secured against the side of a wall by any suitable brackets the same as an ordinary kitchen sink, and can be used for all the purposes of a kitchen sink. Any other similar rectangular vessel, such as a stationary wash basin, can be used to support the washing machine.

In order to provide a means for occasionally washing small articles of clothing the small compartment or chamber 9 has a wash tub 16 secured to its bottom. A box 17 is provided and is hinged to fit loosely in the compartment 9 over the wash tub. This box may be removed and replaced by hand, and is covered by the lid 14 when the washing machine is not in use. Two brackets 18 are secured to the bottom of the box, and have notches 19 in their tops.

A removable horizontal shaft 20 is provided, and has rectangular end portions 21 which fit in the notches 19. The shaft 20 has a cylindrical portion 22, and a beveled toothed segment 24 is mounted to rock on the part 22. This segment has a hub 25, and is retained in place on the shaft between a

pin 26 and a shoulder 27. The hub 25 has parallel grooves 28 formed in it, and the segment has sockets 29 secured to it in line with the grooves 28. The segment is oscillated by means of a removable handle 30, having a forked end portion 31. The forked end portion is slid in the grooves 28 and into the sockets 29, so that the handle rests on the hub of the segment.

A beveled toothed wheel 34 is arranged to mesh into the segment 24, and it has a hub 35 which is journaled in a hole or bearing 36 in the bottom of the box. A vertical shaft 37 is provided, and has a rectangular portion 38 which engages with a corresponding opening in the wheel 34. The shaft 37 is sustained by a pin 39 which projects from it, and a washer 40 between the said pin and wheel. The upper end of the shaft 37 has a shaft bearing 41 which is journaled in a hole in the horizontal shaft 20.

The lower end portion of the vertical shaft 37 has an agitator 42 on it which works in the wash tub 16, and is used to wash small articles in the usual way. The agitator preferably has a hub 44 which is mounted to slide vertically on the lower rectangular end portion of the vertical shaft, and the shaft has a projection 45 on its lower end which fits in a recess in the hub, and prevents the agitator from dropping off the shaft.

The box together with the mechanism in it can be removed and replaced as often as desired, and when the washing machine is in use the wet clothes can be put into the larger compartment to drain. When the washing machine is not in use the handle is removed, and is laid down inside the box, and the small compartment is closed by the lid 14. The device can be used as a kitchen sink when the lid is on, and it can also be used as a sink or wash tub with the lid 14 and the box 17 and the washing mechanism removed from the larger compartment.

An outlet valve 46 for water is secured to the bottom of the wash tub, and is connected to the drain pipe 15 by a pipe 47.

When the box is hinged to the outer vessel, the bottom of the box is provided with a removable section 48 to get out the agitator.

What I claim is:

1. The combination, with a stationary supporting vessel, and a wash tub secured to the bottom thereof; of a removable box hinged at its top edge to the top edge of

the said vessel and adapted to rest on the bottom of it, said box being provided with a removable section in its bottom over the wash tub, a horizontal shaft arranged inside 5 the box, a beveled toothed segment supported on the said shaft, a removable handle for oscillating the toothed segment, a beveled toothed wheel meshing in the toothed segment and journaled in the said 10 removable section, a vertical shaft revolved by the said wheel, an agitator mounted on the vertical shaft inside the wash tub, and a lid which closes the removable box when the

operating handle is removed from the toothed segment. 15

2. A combination of parts as set forth in claim 1, the said vertical shaft being rectangular and engaging with a corresponding hole in the beveled toothed wheel and having a shaft bearing at its top which is journaled in a hole in the horizontal shaft, and means which support the vertical shaft from the beveled toothed wheel. 20

In testimony whereof I have affixed my signature.

EDWARD L. GUSTAFSON.
